his Attorney.

UNITED STATES PATENT OFFICE.

WILLIAM F. NEPPER, OF CINCINNATI, OHIO.

DESIGN FOR A PAVING-BLOCK.

SPECIFICATION forming part of Design No. 23,919, dated December 25, 1894.

Application filed October 6, 1894. Serial No. 525,159. Term of patent 14 years.

To all whom it may concern:

Be it known that I, WILLIAM F. NEPPER, a citizen of the United States, residing at Cincinnati, in the county of Hamilton and State of Ohio, have invented and produced a new and original Design for Paving-Blocks, of which the following is a specification, reference being had to the accompanying drawings, in which—

10 Figure 1 is an elevation of a paving block showing my design; and Fig. 2 is a plan view of the same.

15 The leading feature of my design consists in a polygonal flat-bottomed base, surmounted by a conoid-shaped crown, the latter having a truncated, convex top with a rounded edge or bearing periphery.

A represents the base having flat-bottom A', and six vertical plane sides or faces a, the latter forming a hexagon in horizontal outline. 20

B is a conoid-shaped crown surmounting said polygonal base, and having a convex, truncated top or head b, the bearing-periphery b' of which is rounded, as best seen in Fig. 1.

I claim—

25 The design for a paving block, as herein shown and described.

In testimony of which invention I have hereunto set my hand.

WM. F. NEPPER.

Witnesses:

JOHN E. JONES,
JOHN C. SCHWARTZ.
